United States Patent Office

Des. 222,311
Patented Oct. 12, 1971

222,311

OUTDOOR COOKER

Judkins E. Wilkinson and Clarence R. Smith, Birmingham, Ala., assignors to Atlanta Stove Works, Inc.,

Filed Dec. 4, 1970, Ser. No. 26,288

Term of patent 14 years

Int. Cl. D7—02

U.S. Cl. D81—10

FIG. 1 is a perspective view of an outdoor cooker showing our new design; and,

FIG. 2 is a perspective view showing the opposite side of the outdoor cooker from that shown in FIG. 1.

We claim:

The ornamental design for outdoor cooker, as shown.
